UNITED STATES PATENT OFFICE

2,458,138

ELECTROMAGNETIC RECEPTACLE
FOR LAMPS

Benjamin Waite Blanchard, Jr., Pine Hill, N. J.

Application June 25, 1945, Serial No. 601,362

2 Claims. (Cl. 240—52.15)

1

My invention relates to new and useful improvements in electro-magnetic receptacles for lamps, and has for one of its objects to provide an exceedingly simple and effective device of this character that may be readily connected to a source of electric supply, particularly the ignition and/or lighting systems of an automobile, and magnetically affixed to a metallic supporting member.

Another object of this invention is to so construct the electro-magnetic receptacle for lamps that it will be shock-proof to a person handling the same and also unaffected by outside moisture, especially rain and snow, and electrically conductive articles.

A further object of the present invention is to provide an electro-magnetic receptacle for lamps wherein the electro-magnet is electrically independent of the shell or casing and connected in parallel with the spring contacts for the lamp whereby a person may carry the device about without the possibility of receiving an electrical shock.

A still further object of this invention is to provide improved means for combining the electro-magnet and the spring contacts in a unitary inside structure and including novel means for fastening the unit inside of the shell or casing.

With the above and other objects in view this invention consists of the details of construction and combination of elements hereinafter set forth and then designated by the claims.

In order that those skilled in the art to which this invention appertains may understand how to make and use the same I will describe its construction in detail referring by numerals to the accompanying drawing forming a part hereof, in which:

Fig. 1 is a view in elevation of the complete assembly of the electro-magnetic receptacle for lamps.

Fig. 2 is an enlarged sectional elevation of the receptacle per se, on about the line 2—2 of Fig. 5.

Fig. 3 is a sectional elevation of the electro-magnet, spring contacts and hanger of the inside unit, taken on the line 3—3 of Fig. 2.

Fig. 4 is an isometric view of said inside unit.

Fig. 5 is a top plan view of the same.

In carrying out my invention as herein embodied 10 represents a hollow casing or shell of any suitable material fashioned to provide a body 11 of greatest diameter, a waist 12 of slightly smaller or an intermediate diameter and a neck 13 of still further restricted and smallest diam-

2

eter. The casing or shell is open from end to end and between the body and waist is an annular shoulder 14 while between the waist 12 and the neck 13 is an annular ledge 15.

5 The inside unit consists, generally, of an electro-magnet, spring contacts and a hanger. The electro-magnet is illustrated as comprising an iron core 16, a coil or winding 17 of enameled wire, a magnetic head 18 and a non-magnetic disc 19. Supplementary to the above mentioned elements is an inner insulating sheet or disc 20 between the coil and the magnetic head, an outer insulating sheet or disc 21 on the outer face of said head, and a covering or jacket 22 surrounding the coil or winding 17.

A U-shaped hanger 23 is mounted on the outer insulating sheet 21 and is secured to the magnetic head 18 by any suitable fastening means 24 so that neither the hanger nor fastening means is electrically connected with any current. The ends of the hanger 23 project outwardly and have apertures 25, the walls of which are screw threaded for a purpose to be presently described.

20 Also mounted on the outer insulating sheet 21 are two spaced electric conductive spring contacts 26 and 27, and these are positioned on opposite sides of the bridge of the hanger 23 with their free ends projecting in opposite directions and overlying the said bridge of the hanger.

25 Said spring contacts 26 and 27 are secured to the magnetic head 18 by the respective fastening means 28 and 29 which pass all the way through said magnetic head for connection with opposite ends of the coil or winding 17. For purposes of

30 illustration said fastening means are shown as securing bus strips 30 and 31, respectively, Fig. 3, in place. The bus strip 30 is electrically connected to the inner end of the coil or winding while the bus strip 31 is electrically connected to the outer end of said coil or winding.

35 It is obvious that other ways can be utilized for providing the electrical connections between opposite ends of the coils or winding and the spring contacts, for example, the ends of the wire of the coil can be projected through the parts and secured to said spring contacts.

The inside unit described above is inserted into the body until the outer insulating sheet 21 contacts the shoulder 14. Screws 32 are then projected through holes in the ledge 15 and into the threaded apertures in the hanger 23 which will draw the inside unit tightly into the casing or shell where it will be firmly held with the spring contacts 26 and 27 in alignment with the opening

through the neck 13. Previous to the inside unit being assembled in the casing, the wires or conductors 33 and 34, of the flexible cord 35, are attached to the respective spring contacts 26 and 27 and the cord projects through a hole in the side of the casing. To the outer ends of said wires 33 and 34 are attached suitable electrical connectors 36, such as spring clamps.

An electric two-point contact lamp or bulb 37 of well known construction is fitted into the neck 13, which has bayonet slots 38 to receive the pins on the side of the lamp base, and the pair of terminal contacts on said lamp are engaged with the spring contacts 26 and 27 for completing a circuit through the lamp filament. Any suitable guard 39 for the lamp or bulb is provided and is carried by the casing or shell.

In practice, the conductors 33 and 34 are connected with opposite poles of a source of current, one with the "hot" side and the other with the ground or return side. This will complete a light circuit through one of the conductors, as 33, the spring contact 26, the terminal contacts and filament of the lamp 37, the other spring contact 27 and the other conductor 34. Simultaneously a magnet circuit will be completed through one of the conductors, as 33, the spring contact 26, fastening means 28, the bus strip 30, the coil or winding 17, the bus strip 31, fastening means 29, the spring contact 27 and the conductor 34, thereby energizing the electro-magnet so that the lamp receptacle, through the core 16 only, will magnetically adhere to any metallic surface against which the device is placed. Since both the light and magnet circuits are insulated from the casing, the receptacle may be picked up and carried about without any fear of receiving an electrical shock due to grounding through a person's body, and further, should any electric conductive substance come in contact with the casing and a grounded article, no short circuit will occur that might release the receptacle and extinguish the light.

From the foregoing it will be apparent that I have provided a lamp receptacle which is exceedingly useful as a trouble lamp for furnishing light in out of the way places while leaving a person's hands free for work, advantageous as an extension light, beneficial as a flash light and helpful in many other ways.

Of course I do not wish to be limited to the

exact details of construction herein shown and described as these may be varied within the scope of the appended claims without departing from the spirit of my invention.

Having described the invention what I claim as new and useful is:

1. In an electro-magnetic receptacle for lamps, a casing fashioned to provide a body of one diameter and a waist of smaller diameter with an annular shoulder between them and a neck of still smaller diameter with an annular ledge between said waist and neck, an inside unit comprising an electro-magnet including an enameled wire coil and a hanger and a pair of spring contacts insulated from each other and electrically connected to opposite ends of the coil of the electro-magnet, means engaging the ledge of the casing and the hanger of the inside unit to draw the latter against the shoulder of the casing and hold said inside unit within the casing so that the spring contacts are in alignment with the neck to permit the terminal contacts of a lamp to engage said spring contacts when the lamp is mounted in the neck, and conductors to supply current directly to the spring contacts and through them to the coil of the electro-magnet.

2. In an electro-magnetic receptacle for lamps, a tubular casing open from end to end and fashioned to provide a ledge and shoulder in vertically spaced relation, an inside unit comprising an electro-magnet including a coil surrounding a core which projects below said coil and a hanger, and a pair of spring contacts insulated from each other and electrically connected with the coil, screws projected through the ledge of the casing and threaded into the hanger to draw a portion of the inside unit against the shoulder and leave the outer end of the magnet core protruding below the casing, and conductors connected to the spring contacts.
